UNITED STATES PATENT OFFICE

LEON M. GIBBS, OF CHICAGO, ILLINOIS, ASSIGNOR, BY MESNE ASSIGNMENTS, TO
TELESWITCH CORPORATION, A CORPORATION OF ALABAMA

METHOD AND APPARATUS FOR DIRECTING THE SWITCHING OF RAILWAY CARS AT
YARDS AND TERMINALS

Application filed February 8, 1927, Serial No. 166,762. Renewed June 26, 1929.

My invention relates to a new and improved method for controlling and directing the switching of railway cars at yards and terminals and to apparatus best suited for carrying my said process into effect.

In Letters Patent No. 1,741,229, I have shown and described a method and apparatus of the character above stated which provides in the yard master's office a dummy switch 10 yard corresponding substantially to the railway car switch yard, and provides dummies, representative of railways cars, which are adapted to be shifted about in the dummy yard to correspond with the shifting of railway cars in the main yard. In that invention each dummy was equipped with means to carry data corresponding to its respective railway car and it was contemplated that the dummies would be carried from yard to yard 15 following their respective railway cars.

My present invention contemplates that the dummies may be kept at one yard and assigned temporarily to units of railway rolling stock while in that particular yard territory. 20 Therefore each yard will be equipped with the requisite number of dummies according to its car capacity and means will be provided capable of functioning automatically as railway cars are shifted in the main yard to cause 25 dummies to be correspondingly shifted and placed in the dummy yard, thereby indicating by their location in the dummy yard and the car data each carries the location, destination, car number, etc., of their respective corresponding railway cars in the main yard.

My present invention contemplates the dummies with means to carry all data necessary for switching purposes relative to the 30 correspondingly placed railway cars in the main yard, such data being applied to a dummy as said data is received relative to each incoming railway car and contemplates placing each dummy initially in a position 35 on the dummy yard corresponding to the position occupied by its respective railway car, after which the same dummy will maintain said corresponding position automatically.

My invention further contemplates the

provision of electro-magnetically controlled means which will cause each dummy thus to move and place itself in the dummy yard to correspond with its respective railway car through all switching operations of the latter, and finally to be collected in a train or cut of cars preparatory to leaving the yard and to follow their departing railway cars onto a dummy track representing the outgoing main line track where the dummies will 55 come to rest and be stripped of their records and returned to storage for further use.

My invention further comprises the novel means selected for carrying into effect the above described method of controlling and directing the switching of railway cars, and further comprises novel details of construction of the dummies and the several engaging and controlling elements co-acting therewith so that the flange actuated electric 60 switches in the main yard tracks will act automatically to select and advance the dummies in correspondence with the advancement of their respective control cars in the main 65 yard.

In the accompanying drawings which form a part of this specification, I have sought to illustrate only what I regard as the preferred embodiment of the apparatus above defined.

In these drawings:—
Fig. 1 is a plan view broken away at its ends showing a dummy switch yard comprising a main line track extending through the yard, two parallel straight classification tracks, and lead tracks connected with the main and classification tracks by means of switches.

Fig. 2 is a diagrammatic layout of one set of electric circuits and the control means therefor as used for one straight section of the yard track.

Fig. 3 is a view in side elevation of a section of the main yard track carrying a pair of wheel flange actuated electric control switches for the circuits leading therefrom.

Fig. 4 is a cross-sectional view, partly broken away, taken on the line IV—IV of Fig. 3.

Fig. 5 is a detail view taken along the line 100

V—V of Fig. 3, showing one of the electric switches carrying trip arms.

Fig. 6 is an enlarged cross-sectional view taken on the line VI—VI of Fig. 7, showing a dummy in side elevation riding upon a dummy track shown in cross-section, the dummy being held in position by the combination dummy lock and switch, which is shown in its car locking position.

Fig. 7 is a vertical cross-sectional view taken on the line VII—VII of Fig. 6.

Fig. 8 is a view in end elevation illustrating the electro-magnet actuated control switch for the electric circuits leading therefrom.

Fig. 9 is a side view of Fig. 8.

Fig. 10 is an enlarged detail side view of the dummy.

Fig. 11 is a cross-sectional view of the dummy taken on the line XI—XI of Fig. 10.

Fig. 12 shows how the dummy yard switches are thrown always when the corresponding main yard switches are thrown and how they are maintained in corresponding positions.

Fig. 13 is a diagrammatic layout of one set of the electric circuits and the control means therefor as used for one V-section of the yard track and the corresponding V-section of the dummy track.

Fig. 14 is a view corresponding to Fig. 6 with the parts in the position occupied when the magnet is energized.

Fig. 15 is a detail cross-sectional view on the line XV—XV of Fig. 6.

Similar reference numerals refer to similar parts throughout the drawings.

In the embodiment of my invention illustrated, I have shown in Fig. 13 a diagrammatic layout of one end of a conventional and very simple switch yard comprising a main line approach track 20 and a yard track 22. A lead track 23 diverges from the main line track 20 and is connected with classification tracks 25 and 26, the usual and customary arrangement of switch points and frogs being provided in the main line and lead tracks. In the dummy yard shown in Fig. 1 I show main line approach tracks 20^a and 21^a connecting with a yard track 22^a, lead tracks 23^a and 24^a, and classification tracks 25^a and 26^a, all arranged to correspond with the similarly numbered main yard tracks so far as shown, and in like manner the dummy tracks are equipped with switch points for the distribution of the dummies throughout the dummy yard tracks in correspondence with the distribution of their respective railway cars on the main yard tracks. I show in Fig. 7 how the dummy yard is mounted upon a suitable base or support 27 and the tracks thereof are formed by bent metal members 28 and 29, each having inturned base flanges 30, which are suitably secured to the base 27, and each having in-

turned top flanges 31 and 32, respectively, which flanges lie in the same horizontal plane and are spaced sufficiently at their free edges to provide a track slot for the passage of the arms 33, a pair of which depend from each dummy top 34 and are connected to a bottom dummy element 35. Each of the arms 33, carries two pairs of overhung wheels 36 which receive between them the track flanges 31 and 32 and ride thereon and serve to hold the dummy against disengagement from its tracks. The rollers are mounted on shafts 37 fixed at their center in the arms 33 and provided with any suitable type of wheel bearing. The top of each dummy carries a spring clip 38 adapted to hold in place thereon any data that it is desired for the dummy to carry relative to its respective railway car. The bottom member 35 of each dummy, which is rigidly connected to the dummy top by a pair of arms 33, is provided with side flanges 39, each of said flanges being provided with a series of equi-distantly spaced similar laterally outstanding lugs 40 formed by parallel vertical ribs integral with or otherwise attached to the side flanges 39. Each bottom member 35 is preferably connected by screws 41 to the arms 33, as indicated more clearly in Fig. 10, and I mount across the top of the flanges 39 in the middle of the base element a cross bar 42 by means of screws or other connections 43, and I suspend from this cross bar what I term a coupling plate 44 having a central top shank 45 which projects upwardly through the cross bar 42 and has a stop collar 46 keyed thereon to limit the down travel of the plate. A coil spring 47 is interposed between the top of the plate and the bar 42 and serves normally to thrust the coupling plate 44 downwardly into engaging position with coil spring belts hereafter described. Said plate 44 has end lugs 48 to limit its up travel by engaging the bottom of the member 35. As shown in Fig. 1, the slot formed between the approach rails 31 and 32 is designated as the dummy track section 20^a at one end and at the other end as the track section 21^a and so on throughout the dummy yard.

The track plates forming the dummy classification tracks 25^a and 26^a, terminate at their ends adjacent to the tracks 23^a and 24^a in switch plates 49 for the track 22^a and for the track 25^a, and each one of these switch points is fast on a pin 51 which extends down through the base and is suitably journaled therein so that the switch plate is free to swing horizontally in the plane of the flanges 31 and 32. On each of these pins 51 I rigidly secure an armature 52 normally pressed by a spring 53 so as to hold the switch point in the full line position shown in Fig. 1, and I suitably mount on the base, in position to co-act with each arm 52, a magnet 54 which, when energized, will throw the switch against

the action of spring 53 so as to guide the dummy cars into the desired classification track. In Fig. 1, to avoid undue confusion, I have shown only one of the switch plates provided with the actuating mechanism described above, but it will be understood that a similar mechanism is provided for each switch plate and as shown in Fig. 12 each switch magnet 54 is included in a circuit 55, which includes 5 a make and break switch 56 and is connected to a suitable source of power. The main track switch points 57 are connected by a switch operating rod or bar 58, to which bar is loosely connected an electric switch arm 59. 10 This latter arm co-acts with contacts 56 to close the circuit 55 to the magnet 54 for controlling the corresponding switch in the dummy yard, and thus as each track switch is moved the corresponding dummy switch will 15 move in the same manner, being shifted in one direction by the action of the magnet 54 and in the other direction by the spring 53 when the circuit 55 is opened. Thus I maintain the dummy yard switches at all times 20 in corresponding positions with their respective main yard switches.

Both the main yard, when automatically operated, and the dummy yard are divided into corresponding control sections which 25 will perhaps best be understood by reference to Fig. 1, wherein I show the sections into which the dummy yard is divided. The first section lies in the approach track 20^a and may extend any desired length along that track but as at present contemplated each section will accommodate as a maximum 20 dummies. Opposite this first section is an 30 endless dummy actuating belt 61. The next control section will be a V-section and on one side will extend from the approach track 20^a into the track 22^a coextensively with the actuating belt 62, and the other side will extend from the track 22^a along the lead track 23^a coextensively with the actuating belt 63. 35 The dummy coupling plate 44 is wide enough to engage the converging ends of the belts for a V-track control section. The next V-control section extends from the last mentioned section along track 23^a and 25^a coextensively with the actuator belts 64 and 80. Another section lies opposite the belts 65, in 40 the track 25^a; another section lies opposite the belts 66, in track 26^a; 70, in track 23^a; and 71 in track 24^a. The lead track 24^a will 45 have sections corresponding to these for the lead track 23^a which will include the belts numbered 67 and 84 for one V-section and 68 and 94 for the other V-section. The approach section in track 21^a is coextensive with the belt 69. The short belts 70 and 71 at each side are sufficient in length to transfer the dummies from belt 66 to the belts 64 and 67. A dummy lock and switch, hereinafter 50 described, is provided at the termini of the several dummy yard sections.

A motor 72 will drive a pulley 73 for actuating the belt 62, and by a train of gears 74, 75 and 76 will drive a pulley for actuating the belt 63. The belt 61 is driven by a similar motor at the commencement of its track section and returns over an idler on the shaft of the motor 72. The idler 77 for the belt 63 is mounted loose on a shaft 78 on which is mounted fast the driving pulley for the belt 64, this shaft being driven by a train of gearing from a motor 79, which also serves to drive the belt 80 for the track section connecting the lead track 23^a with the intermediate section in the track 25^a. The belt 80 returns over an idler 81 loose on a shaft 82 on which is a loose idler pulley for the belt 65. The other end of the latter belt is driven by a motor 83. A belt 84 passes over an idler on the shaft 85 of the motor 83 and is driven by a pulley fast on the shaft of a motor 86 to transfer dummies from the belt 65. The motor 86, by a train of gearing, serves to drive the belt 67, the other end of which passes over an idler loose on a shaft 87. A motor 88, by the gearing shown, serves to drive the belt 68 and its shaft supports the idler 89 for the belt 69, which at its other end is driven by a motor, not shown. It will thus be seen that the motor 79 drives the belts 64 and 80 which control what I term a V-section of the dummy yard. In like manner the motor 72 drives V-belts 62 and 63. The motors 86 and 88 likewise control the V-belts at the other end of the yard. A motor 90 serves to drive the belt 66 and by means of a chain 91 or the like will drive the belts 70 and 71 through the gearing shown. A motor 92 acts to drive the belt 93 which extends from the belt 62 at one end of the track section 22^a to the belt 94 at the other end, this latter belt 94 being driven by the motor 88 and turning about an idler loose on the drive shaft of the motor 92.

It will thus be seen that all of the tracks of the dummy yard are provided with dummy actuating belts which overlap so that they are capable, when driven in the correct direction, to pass a dummy from the track 20 to 21^a and vice versa over all of the interposed tracks 22^a, 25^a and 26^a. It is to be understood that each of the motors described is a reversible motor, preferably an electric motor, capable of driving the belt or belts controlled by it in either direction.

The belts, which I propose to employ, are preferably formed by a coiled wire shown more clearly in Figs. 6, 7, 10 and 11, and in each endless belt I interpose two equidistantly spaced blocks 96, see Figs. 2 and 6, which divide the belt into two equal sections and are intended to provide a positive element in each flight of the belt which, by engaging the coupling plate 44 on the dummy, will positively move the dummy, whereas it is contemplated that the coil spring portion of

the belt will yield and pass the dummy coupling plate when substantial resistance to the dummy's movement occurs.

The division points between the track sections of the main yard are defined by the location in the main yard tracks of the flange actuated switch mechanism, each comprising the switch arms 98 and 99. The divisions in the dummy yard are defined by the location of a dummy lock and switch mechanism shown in Figs. 6, 7, 14 and 15. When a railroad car crosses from one side to the other of a switch mechanism, its corresponding dummy is caused to move across the corresponding dummy lock and switch mechanism, which is correspondingly located in the dummy yard. I have chosen to utilize the car wheels as the controlling factor in the above switch operation and to this end, as will be seen more clearly in Figs. 3 to 5, I provide at each terminus of each main track section a similar double switch mechanism which is illustrated in the above figures and all being alike the description of one switch mechanism will apply to all. In order that the switch mechanisms and their location may be better understood, in Fig. 13 I designate the switch mechanism by the numerals 98, 99, and each mechanism comprises a pair of reversely inclined switch arms 98 and 99, which are similar except in respect of the direction of their inclination. Each arm is pivotally mounted on a bearing pin 100 having a threaded shank 101 which is bolted by a nut 102 to the web of the adjacent main track rail 103. This bearing pin may be mounted in any other suitable way to meet railroad requirements. Fast on each pin 100 is a collar 104 carrying a stop lug 105 which overhangs a trip arm 106, which arm is engaged beneath by a coil spring 107 secured on a pin 100 and adapted to counteract the weight and hold the arm up against the stop 105. This arm 106 is rigid with a bearing sleeve 108 carrying at its outer end a switch bearing arm 98 or 99, as the case may be. A switch is mounted on the free end of each arm and comprises an angle bracket 109 having spaced blades 110 of a knife switch suitably mounted thereon and insulated therefrom by 111. A knife switch arm 112 is pivotally mounted with its inner end projecting inwardly from the arm 98 or 99 and its forward end adapted to engage between the contacts 110, being normally held disengaged by the spring 113. The switch arm is mounted in a slot 114 in the end of the arm 98 or 99 and its inner end is held by spring 113 against the inner wall of said slot. Midway between the pins 100 of each switch mechanism I mount a second pin 100^a, similar to 100, and on this pin is mounted a sleeve 115 carrying rigid at its inner end an upstanding trip arm 116 and at or near its outer end a vertical pin 117 disposed to engage and close the switches on the

adjacent arms 98 and 99. The trip 116 carries beneath it a pin 118 engaged between the ends of a coil spring 119 mounted loosely on the pin and held to its working position by the interposed angled end 120 of a bracket 121 secured rigidly to the pin 100^a. By this arrangement, as the arm 116 rocks to right or left, one end or the other of the spring acts to return it to vertical position and the spring arms act to hold it in vertical position. The trip arm 106 for each of the switch bearing arms 98 and 99 are so disposed with relation to the trip arm 116 that the flange of a car wheel that has moved the arm 116 to either of its dotted positions shown in Fig. 3, will likewise depress the then adjacent trip arm 106 and will, if the wheel passes over the latter, release the arm 116 to snap up in doing which pin 117 will strike the switch 112 on the then adjacent arm 98 or 99 and will close the switch at 110, but if the wheel does not move far enough to entirely release the arm 116 and then backs, the switch will not be moved into the path of the pin 117 and will not be closed as the arm 116 swings back up. The switch is closed only momentarily, as the moment the pin 117 passes the switch its spring 113 opens it and thus only an impulse of current is passed through the wire circuit 122, 123, or 122^a, 123^a, according to whether the switch on arm 98 or 99 is closed.

The circuit 122, 123 is connected to a suitable source of power and includes a magnet 224^a, see Fig. 2. In like manner the circuit 122^a, 123^a includes a magnet 124^a. From the foregoing description it will be seen that at any switch mechanism the switch on arm 99 is closed by a car wheel approaching from the right and correspondingly the switch on arm 98 is closed by a wheel approaching from the left. Hence, the switches on the arms 99 control the travel to the left of dummies across the dummy yard, and in like manner the switches on arms 98 control the travel of the dummies to the right across the dummy yard. In Fig. 2 I show the switches for the left and right hand ends of a given straight main track section for controlling the left and right hand movement of dummies out of the corresponding dummy yard section. The manner in which the track switches 98 and 99 control the exit of dummies out of right and left ends of the section of the dummy yard corresponding to said main yard section will now be described by reference to the dummy track section opposite belt 93.

Referring to Figs. 2, 8 and 9, I have shown a typical magnet 124^a connected in the circuit 122^a and 123^a and this magnet is shown mounted upon a base 125 which also carries a second magnet 126. Above the magnet 124^a is a guide bracket 127^a having parallel top and bottom lugs 128^a and 129^a in which an armature 130^a is slidable with its upper end shouldered to engage the lug 128^a so

as to limit its up travel responsive to the action of a spring (corresponding to 131 in Fig. 9), which is connected to the lug 128^a and to a screw eye (corresponding to 132, Fig. 9), on the armature 130^a. The armature is adapted to be drawn downward by the magnet 124^a and when thus drawn it carries with it a pawl 133^a which engages a ratchet wheel 134^a suitably journaled at the upper end of a standard 135^a. This pawl is held by a spring 136^a against the ratchet wheel and acts on the downward travel of the armature 130^a to advance the ratchet wheel one step against the action of a spring stop 137^a mounted on the standard 135^a. An annular fiber disk 138^a is fast to the wheel 134^a and has its periphery covered by a band 139^a of copper or like material that carries a lateral spring contact brush 140^a. A spring brush contact 141^a engages this disk band 139^a and is connected to a circuit 142^a which leads, as shown in Fig. 2, to a magnet 143^a and thence passes by a circuit 144^a, see Figs. 2 and 6, to the center contact 145^a of a three point switch plate 146^a (Fig. 6). The contact 145^a is engaged by a switch arm 147^a connected by a wire 148^a to the positive line circuit. Mounted on each base 125 carrying a magnet 124^a, is a magnet 126 with which are associated parts identical in structure with the parts associated with magnet 124^a and numbered from 127^a to 139^a, all inclusive, except that the fiber disk 138 is notched to receive a block of insulation 149 upon which normally the brush 140^a rests, thus interrupting a circuit that would otherwise flow from 139 to 139^a. A brush 141 engages band 139 and is in a circuit 142 leading through a magnet 150 to one side of a switch 151 adapted to be closed by a switch arm 152 so that current can flow over line 153 from the motor 92 which has a lead 154 to the negative side of the power line.

The circuit 122, 123 includes the magnet 224^a and is connected across the power line. The magnet 224^a is associated with a second circuit breaker equipment corresponding to that already described in connection with 138^a and to distinguish between the two, the disk this magnet 224^a controls is numbered 238^a corresponding to 138^a and carries a brush 240^a corresponding to 140^a, which contacts with disk 238 corresponding to 138 and having a brush 241 corresponding to 141. From 241 a circuit 242 leads to and includes the magnet 157 and leads thence to a mercury switch 156 and continues therefrom by line 155 to the motor for driving it in a reverse direction from that when current flows to the motor over line 153. When either switch 151 or 156 has been opened by its magnet, one power circuit controlled by it to the motor is interrupted and the other power circuit is closed at the switch, thus insuring that only one power circuit will be connected

at one time to the motor. The brush 241^a for the disk 238^a is connected by the line 242^a with the magnet 243^a and thence by line 244^a with a contact 245^a which, when engaged by the dummy switch arm 147, will have connection to the positive power line 148.

A contact 158^a controlled by switch arm 147^a is connected by a circuit 159^a with the magnet 126 controlling the disk 138 and thence is connected to the negative side of the power line. In like manner a contact 160, controlled by switch arm 147^a, is connected by a line 161^a with the magnet 326 controlling the disk 338, corresponding to the parts 226 and to 238 already described, and forming part of the circuit breaker mechanism for the adjacent track section on the left. From the disk 338^a of this adjacent circuit breaker mechanism a lead 342^a, corresponding to 242^a, extends to the magnet 143^a, and the lead 342, corresponding to 242, leads from the brush 341 shown in this adjacent circuit breaker mechanism to include a switch magnet, not shown, corresponding to 157, for its respective track section and there will be duplicate wiring from such switch magnet to the motor controlling the adjoining belt on the left. In like manner, with respect to the switch arm 147, its contact 258^a will be connected by a lead 259^a with a magnet 426 for the disk 438 of the circuit breaker for the adjacent track section on the right, and from brush 441^a, for disk 438^a of this circuit breaker mechanism, there will be a lead 442^a to the magnet 243^a associated with the switch arm 147. The magnet 424^a controls the circuit breaker 438^a, and all of the parts for each of these adjacent track sections are similarly connected up with the magnets, the circuit breakers, contact arms and track circuit switch mechanisms, all as described in connection with the complete wiring for one track section shown.

The mercury switch 156 for the track section, shown in Fig. 2, is controlled by its respective magnet 150 in a lead from the brush 141 to switch 151 and when this latter switch is closed and the circuit is closed between 138 and 138^a, this magnet 150 will be energized and will rock the mercury switch, breaking the line 155 when the mercury has had time to run to the left hand end of the switch tube. This gives a slow acting switch which will serve as a selector to prevent the switches on two track arms 98 and 99 that happen to be depressed and actuated at the same time, from establishing opposing circuits through 153 and 155 to the motor. If such circuit closing occurs in the main yard tracks, both the magnets 157 and 150 will be energized, but, due to the slow action of mercury switch 156, the switch 151 will open the circuit that energizes the magnet 150 before switch 156 can open and thus this latter switch will not open.

The circuit layout for a straight track section section in Fig. 2 requires slight modification to care for a track section involving a switch, which I term a V-track section, due 5 to the fact that in the dummy track it will involve a pair of belts arranged in V-shape.

A V-track section on the railroad yard will extend from the switch points to a point on each divergent track far enough from the 10 switch points to just permit approaching railway cars on the two divergent tracks to clear each other. In Fig. 13 I have shown a typical circuit layout for a V-track section of the 15 main yard lying between a pair of switch arms 99 at the left and three switch arms 98 at the right lying in the straight track 22 and at the switch for the track 25. As shown, the 20 electric switch arms 98 and 99 for the V-section in this figure are connected up with the magnets 524^a and 324^a which co-act with the 25 disks 538^a and 338^a. It will be observed that both electric switch arms 98 at the main line track switch are connected to the lead 123^a, while three electric switch arms 98, one in the 30 main track 22 and two in the track switch for track 25, are all connected in multiple to the lead 123 to the magnet 324^a so that any one of these electric switch arms is capable of closing the circuit to said magnet with which 35 it is connected, whereas in straight track sections generally only one electric switch arm 98 or 99 controls its respective magnet. This Fig. 13 also shows the connections from the 40 corresponding V-section tracks on the dummy board to the magnets 526 and 326, which are similar to those described in connection with Fig. 2 with the following exceptions, namely:—

1st: The drive of the motor 72 to feed the 45 belts 62 and 63 to the right is controlled by either of two dummy switch arms 147^a, each located at the divergent ends of the dummy track V-section, and the drive of the motor to feed the said belts to the left is controlled by 50 a single dummy switch arm 247 located adjacent to the apex of the dummy V-track section, but far enough therefrom for the dummy to right itself after leaving the dummy track switch. As shown in Fig. 1, such switch arm 55 would be opposite the motor 72.

2nd: The mercury switch 156 is dispensed with in this layout and only the switch 151 is 55 interposed in the circuits 153, 155. If both circuits 153, 155 are energized at the same time, the circuit 155 will control for it will open 153 and hence both leads to the motor cannot be simultaneously closed. The elements 338^a and 338 in this figure are the same parts similarly numbered in Fig. 2, and 738^a 60 and 738 correspond to 138^a and 138 in Fig. 2, except that they are located in the adjacent section of the lead track 23.

Each dummy switch arm 147, 147^a or 247 65 forms part of what I term a dummy lock and switch mechanism which is shown more clearly

in Figs. 6, 7, 14 and 15, it being understood that these several mechanisms are all duplicates in construction and are located at termini of the dummy track sections. The following description of one mechanism therefore will apply to all. 70

I provide a suitable opening 165 in the base 75 27 through which project the base guide lugs 166 of a guide bracket having integral side lugs 167 connected by screws to the base and comprising at each side top guide brackets 168. These guide lugs 166 are connected by a bottom web 169 into which is screwed a guide pin 170 for a coil spring 171 bearing below on the web 169 and above on a web 172 so connecting the side walls of a U-shaped slide frame 173 which comprises spaced side arms connected near their center by the webs 172 and at their bottom by a plate 174 attached thereto and carrying an armature 175 for a magnet 143^a. The spring thus tends to hold the armature and the U-slide 173 in raised position, as shown in Figs. 6 and 7. Above the web 172 one side of the U-slide is provided with an elongated slot 176 through which passes the drive shaft for the belt pulleys which support the overlapping ends of the belts 93, 94, and the other side of the U-slide supports a dummy switch arm 147^a. This slot 176 permits the slide 173 to rise and fall 80 independently of the motor shaft. The upper ends of the U-slide 173 project above their guides 168 and carry elongated horizontal bars 177 which are adapted to engage the side lugs 48 on a dummy's coupling plate 44 throughout the dummy's operating positions 85 relative to the lock mechanism in question. The upper ends of the slide above the bars 177 are reduced and tapered to provide wedge points 178 which are adapted to fit with ample operating clearance between a pair of side lugs 40 on the dummy. The dummy switch arm, indicated as 147^a, is pivotally mounted on a stud 179 at an intermediate point on one side of the U-slide 173 and its 90 upper end is provided with a bent-over lug 180 which normally overhangs slightly above the path of the adjacent dummy lugs 40. The lower end of this switch arm carries a brush 181 which co-acts with the contacts on the three point switch plate 146^a carrying the three contacts 145^a, 158^a and 160. The circuit 148^a leads to this brush 181 and the switch arm is normally held in vertical position by the engagement therewith of a spring 182 which will permit it to play over the switch points but will restore it when released to position over contact 145^a. It will be obvious that when the U-slide is drawn downwardly by the magnet 143^a, as shown in Fig. 14, it will draw the lug 180 of this switch arm into position between the middle pair of lugs 40 on the dummy, as shown in Fig. 6, and at the same time it will lower the taper point 178 below the path of the lugs and will also per- 95

mit the spring 47 (Fig. 10), to lower the coupling plate 44 into position to engage the overlapping belts below the dummy and to be advanced according to the direction of the movement of the belts. As the dummy moves an approaching lug 40 engages the lug 180 on the switch arm 147^a and throws it to the right or left, according to the dummy's direction of movement, off of contact 145^a and onto contact 158^a or 160. This shifting of the switch occurs just after the tip of the wedge 178 is in position under the space between the next pair of lugs 40 on the right or the left and as soon as the shifting of the switch takes place, the circuit is broken to the magnet 143^a and the spring 171 snaps the slide 173 upwardly, interposing the wedge point between the next pair of dummy lugs. The rising movement of the lug 180 causes it to ride up the side of the lug last passing the point 178 until it clears the top of this lug, when it will swing back to vertical position responsive to the action of its spring 182, again restoring the circuit to contact point 145^a. As the dummy switch arm 147^a engages either contact 158^a or 160 it will serve to close a circuit to magnet 126 for the track section on the right, or 326 for the track section on the left, according to the direction in which the dummy is moving, and the closing of either of these circuits will act to advance its circuit closing disk 138 or 338 one step, thus advancing the insulator block 149 or 349 one step. At the same time whenever the corresponding flange actuated electric switch arm is depressed and actuated it will, by energizing the magnet 124^a or 324^a cause the disk 138^a or 338^a to be advanced one step, carrying with it the circuit closing brush 140^a or 340^a. In ordinary operation the passage of a car wheel over a flange actuated electric switch will thus advance one of the brushes 140^a, or 340^a, etc., one step and thus will disengage it from the insulator block 149 or 349 in the control disk paired therewith and will thus establish a circuit across the disks which will cause its respective belt movement carrying the dummies which are engaged therewith toward a dummy lock and switch mechanism, which mechanism will act as above described to allow the passage of one dummy lug and to cause insulator block 149 or 349 to again break the circuit flowing through paired disks. One important feature to be noted here is that the movement step by step of the dummy is not necessarily effected contemporaneously with the corresponding wheel movement over a flange actuated electric switch because as each wheel on a railway car traverses said switch it acts to advance its respective control disk 138^a or 338^a, etc., one step for each passing wheel, thus carrying the contact brush 140^a, 340^a, etc., as many steps in advance of the insulator block 149 or 349 as there will be wheels passing the said switch.

When contact brush 140^a, etc., is in advance of block 149, dummy lugs will approach a corresponding dummy lock and switch mechanism and the dummy mechanism controlling its side of the circuits to the paired disks will, as rapidly as lugs are passed and step by step, advance disk 138 until as many dummy lugs have passed the dummy lock and switch mechanism as car wheels have passed a corresponding flange actuated switch, and when this occurs it will be apparent that the insulator block will have caught up with and again assumed position under the contact plate 140^a. Thus a flange actuated switch mechanism sets up step by step a car controlled element for each passing wheel and the related dummy actuating mechanism, as it moves the dummies, will advance the paired dummy controlled element step by step until it has advanced the same number of steps as the car controlled element, whereupon the operation of the control mechanism for that particular car shifting movement is completed.

Inasmuch as occasion may arise from time to time to remove dummy cars from the dummy yard, I provide at suitable points in the track any desired number of slides 184 (see Fig. 1), which will open the dummy track at one side sufficiently for a dummy to be lifted out bodily.

In operation, it is to be understood that with advance information as to the number of cars in an approaching train or cut and the number of flanged wheels of the locomotive or caboose, there will be provided in the corresponding approach track of the dummy yard dummies corresponding in number to the cars and if the locomotive or caboose has wheels on one side not representing four or a multiple of four, then I will use special dummies having one or more of the middle lugs 40 removed so that these dummies containing two or three lugs to the side can be combined with standard dummies or with each other so as to make up any desired number of lugs to correspond with the number of flanged wheels on the locomotive or caboose. In this manner the dummy train will provide on each side the number of lugs corresponding to the number of flanged wheels on one side in the approaching train and, having set the dummy cars in engagement with the approach track belt 61 or 69, the apparatus is now ready to function. As each flanged wheel of the train passes over the initial flange actuated switch mechanism it will, in the manner described, cause the pin 117 of that mechanism to trip the switch on arm 98 or 99, according to the direction of movement of the car wheels and thus each wheel will serve to close a circuit to a magnet corresponding to 124^a. Each energization of either of such magnets will advance its respective circuit closing disk corresponding to

138^a one step, thus causing such disk to be advanced step by step and as rapidly as the wheels pass over and make and break the switch controlling its respective actuating magnet. In the manner described, the movement of the circuit closing disk corresponding to 138^a will start the dummy belt in motion and as each dummy lug passes a dummy lock and switch mechanism at the discharge end 10 of the approach track section, it will in turn advance its respective circuit breaker disk one step, causing it to follow up the circuit closing disk until the insulator block 149 is again presented in position to interrupt the circuit 15 between the paired disks. This permits the dummies to be fed step by step without their movement being necessarily contemporaneous with that of their controlling railway cars, but causes always the circuit between the 20 paired disks to be held closed until dummy lugs, equal in number to the wheels that have acted to advance the circuit closing disk of the pair, have acted on and correspondingly advanced the circuit breaking disk. Whenever 25 a main track switch is thrown, through the circuit connections described, the corresponding dummy switch is similarly thrown and thus the dummies will be moved throughout the yard following up their respective 30 "control" railroad cars, due to the fact that whenever a flanged wheel of a railroad car rolls from one into the next section the mechanism described will move one lug on a corresponding dummy into the corresponding 35 section of the dummy yard and thus the dummies must follow their "control" cars throughout.

By reference to Fig. 2 of the drawings it will be seen that 96 is representative of a 40 dummy actuator controlling a track section and the arrows indicate it as movable in both directions. Let us suppose that the wheel depressed track switches that control this actuator 96, and which are located at opposite 45 ends of a long switch yard track section, happen to be operated at about the same time, due to the fact that cars are moving in or out at the east end of the track while cars are moving in or out at the west end of the 50 same track. This would neutralize the motor and leave the belt idle but for the fact that the step by step control 138, 138^a, and 238, 238^a are connected to the motor driving the belt 96 through relay control switches that 55 act in the following manner, if switch 99 is depressed slightly ahead of the switch 98, as each wheel moves over 99, it will advance 138^a one step and as each wheel indicator on a dummy is correspondingly moved, 138 will 60 follow around one step. So long as 138^a is ahead of 138 this switch 99 will retain control of the motor 92 and will continue to move dummies, but if in the meantime switch 98 has been operated and its element 238^a caused 65 to advance, the moment 138^a and 138 resume

initial position, the control of the motor 92 will come under switch 98 and the elements 238 and 238^a which were left displaced will commence to feed out wheel indicators until they get back to initial position. In other words, when switch 98 or 99 at opposite ends of a track section has once been depressed, it will retain control of the motor 92 until its elements 138^a and 138 resume initial position, whereupon the motor is instantly subject to 70 the control of the other switch 98 and its step by step feed control elements 238 and 238^a which are waiting to exercise this control.

In this manner, while cars moving at one end of a track section actuate switch 98 and 80 control motor 92, cars at the other end may move freely in an opposite direction out from said track section and the necessary dummy control will have been set up on 238^a, step by step, as each car wheel depresses a track 85 switch, and will remain unsatisfied until upon the restoration of the motor to control of switch 99 a corresponding number of dummies shall have moved out of the same dummy yard track section, which will bring elements 238^a and 238 back into initial position 90 and release the motor for the next control operation.

When the dummy train is made up, every 95 dummy carries or has attached to it in any suitable manner way bill data or identifying data corresponding to its respective railway car, and one or more dummies corresponding to the locomotive or caboose are so designated. After the switching operation is completed, the dummy cars follow their control cars into the outgoing approach track and the way bill data and other data is stripped from them and they are ready for future use. It will be noted that the dummy bumpers 100 183 are rounded so that they will not displace 105 themselves relatively in rounding the sharp dummy yard curves.

By the arrangements described, the yard master can have before him in his office an 110 automatic mechanism which will at all times show him the location of his cars and engines and he can follow up the actual movements of all rolling stock in the yard. Also, he can be assured that his cars provide clearance at the switches and he can note the position of his yard switches. It is of course to be understood that the mechanism for carrying out the automatic functions hereinbefore described may be variously modified within the scope and contemplation of my present 115 invention.

When I refer to a car I mean the same to 120 be inclusive of any vehicle such as an engine, tender, caboose or like vehicle adapted for movement on railroad tracks, and by a dummy I mean to include any representation of the railway car capable by its relative displacement over a dummy yard or any representation of the railroad yard to indicate the 125 130

position of the railroad car corresponding to the dummy and preferably the number indicia descriptive of such corresponding railroad car, such indicia including any data that 5 may be desired or needed by the railroad yard master.

What I claim as new and desire to secure by Letters Patent, is:—

1. An improved method for directing the 10 switching of railway cars, which consists in providing a dummy switch yard substantially corresponding to the switch yard for railway cars, providing for each railway car to be handled in the railway switch yard a 15 correspondingly designated dummy, and causing the dummies automatically to move from track to track on the dummy switch yard in substantial correspondence to the movement of their corresponding railway 20 cars in the railway switch yard.

2. An improved method for directing the switching of railway cars, according to claim 1, in which the railway switch yard and the dummy switch yard are subdivided into corresponding track sections, and in which the 25 dummies are caused to pass from one into another dummy track section following the movements of their correlated railway cars between corresponding railway switch yard 30 track sections.

3. An improved method for directing the switching of railway cars, which consists in providing a dummy switching yard corresponding to a car switching yard, the tracks 35 of each yard being similarly subdivided into track sections, providing for each railway car to be handled a dummy carrying identifying data for its "control" railway car, and causing each dummy to move from section to section of the dummy yard tracks following a corresponding movement of its respective "control" railway car from section to section of the railway switch yard tracks.

4. An improved method for directing the 45 switching of railway cars, according to claim 3, in which the control of a dummy's following movements is responsive to the passage of car wheels of its "control" railway car from section to section of the car switch 50 tracks, and in which each dummy has control elements corresponding in number to the controlling wheels of its respective railway car.

5. The herein described method for the switching of railway cars according to claim 3, in which each controlling wheel of each 55 railway car being switched, in crossing track section junctions, causes a step by step movement of its respective dummy across the corresponding track section junction of the dummy yard.

6. In a railway car switching control system, main yard tracks, corresponding dummy yard tracks, dummies on the dummy yard tracks representative of railway cars on the 65 main yard tracks, and automatic mechanism

controlled by the movement of the railway cars from track to track of the main yard to effect a substantially corresponding movement and switching of dummies from track to track in the dummy yard.

7. In a railway car switching control system, a main yard having its tracks divided into control sections, a dummy yard having its tracks correspondingly divided into sections, dummies to correspond with the railway cars to be switched, both yards having corresponding switches, and mechanism automatically responsive to the movement of railway cars from section to section for operating said dummy yard switches and effecting the movement of their corresponding dummies similarly from section to section of the dummy yard.

8. In a railway car switching control system, according to claim 7, mechanisms for shifting the dummies from section to section of the dummy yard tracks, and means to selectively energize said mechanisms responsive to the movement and direction of movement of the corresponding railway cars in the railway 85 switch yard.

9. In a railway car switching control system, a railway yard having its tracks subdivided into control sections, a dummy control mechanism arranged between each two adjacent sections and adapted to respond to the fact and direction of a car movement past it, a dummy yard corresponding to the railway yard and subdivided into similar sections, dummy actuating means for each dummy track section which are adapted to transfer the dummies from end to end of a section, and means responsive to the actuation of the above mentioned dummy control mechanisms for moving the dummy with a step by step movement from section to section of the dummy yard.

10. A railway car switching control system, according to claim 9, in which the mechanism located at each section junction of the railway switch yard comprises electric switch means selectively responsive to the direction of movement of a passing railway car, and in which dummy actuating mechanisms are responsive to the actuation of said switch mechanisms.

11. In a railway car switching control system, railway track sections having at each terminus a wheel actuated trip mechanism, dummy track sections each having a dummy actuating mechanism associated therewith, and means responsive to the actuation of a trip mechanism to energize its respective dummy actuator for moving dummies in a determined direction.

12. In a railway car switching control system, railway track sections having at their junctions a wheel actuated trip mechanism, corresponding dummy track sections having dummy actuating mechanisms associated 130

therewith, and means responsive to the actuation of any above mentioned trip mechanism to energize selectively a dummy actuator in a direction corresponding to the direction of movement of the trip actuating wheel.

13. In a railway car switching control system, main yard tracks divided into sections and having a trip mechanism between adjacent sections, a dummy track similarly divided into sections, dummy actuating means to shift a dummy from section to section, and means responsive to the actuation of any main track trip to energize its respective dummy actuator, and dummies adapted to be shifted by said actuators.

14. A railway car switching control system, according to claim 13, in which each main track trip mechanism selectively controls the direction of motion of two dummy actuating mechanisms adapted to switch a dummy from one to the other of the dummy track sections corresponding to the main yard sections on each side of the wheel actuated trip mechanism.

15. A railway car switching control system, comprising a main yard divided into V-control sections at track intersection and straight control sections connecting the V-control sections, a dummy switch yard correspondingly divided into V-sections and straight sections, car actuated trip mechanisms located at the termini of the main track sections, dummy actuators adapted to move dummies across dummy section termini, and means responsive to the direction of movement of a railway car in actuating a trip mechanism selectively to energize the dummy actuators to shift a dummy across the junction point of dummy track sections corresponding to the junction point in the main track where the actuated trip was located and in a direction corresponding to that of the trip actuating car.

16. A railway car switching control system, comprising a main switching yard divided into control sections with a dummy control mechanism at each section terminus, a dummy switch yard similarly divided into track sections and having dummy actuating belts coextensive with each section, dummies movable on the dummy tracks and adapted to be transferred from belt to belt at track section junctions, and means to energize and control the direction of movement of the belt mechanism for each track section responsive to the dummy control mechanisms at the termini of the corresponding main track section.

17. In a railway car switching control system, a main switching yard divided into control sections comprising straight track sections and V-track sections, the latter extending from the intersection of tracks to the point of clearance for cars on the divergent tracks.

18. In a railway car switching control system, a main switching yard divided into sections, mechanism responsive to the passage of a car from one to another section adapted to advance a circuit closing element step by step, a dummy yard divided into sections, means to move dummies from section to section, and mechanism responsive to the movement of a dummy from one to another section adapted to advance step by step a circuit breaking element associated with the aforesaid circuit closer, said circuit breaker and closer when advanced the corresponding number of steps from initial "open circuit" position being adapted again to break the circuit which they control, and means responsive to the breaking of said circuit to stop its respective dummy actuating mechanism.

19. A railway car switching control system, according to claim 18, in which the flanged wheels at one side of a car serve to control the step by step advance of the circuit closer, and in which a similar number of elements on the corresponding dummy serve to control the step by step advance of the circuit breaker.

20. A railway car switching control system, according to claim 18, in which the railway cars and corresponding dummy cars are provided each with a similar number of trip elements, which trip elements respectively control the step by step movements of the co-acting circuit closer and breaker elements.

21. In a railway car switching control system comprising a pair of electro-magnetically actuated co-acting rotatable elements interposed in an electric circuit controlling a dummy actuating mechanism, means responsive to the movement of a railway car to advance one of the elements step by step, means to close the circuit between said elements when moved from predetermined relative position, and means responsive to the movement of a dummy car to advance the other of said elements step by step back into predetermined relative position, and dummy actuating mechanism operable responsive to said circuit when closed.

22. A railway car switching control system, according to claim 6, in combination with track switches for railway cars, corresponding track switches for the dummy cars, and mechanism to shift the dummy track switches automatically responsive to the shifting of their respective railway track switches.

23. In a railway car switching control system, in combination with a main track yard comprising switches, a dummy track yard comprising corresponding switches, and means automatically responsive to the shifting of any main track switch to similarly shift the corresponding dummy track switch.

24. In a railway car switching control system, in combination with railway car con-

trolled mechanism for advancing and switching a dummy, mechanism operable responsive to the movement of the car to regulate the dummy's advance step by step.

25. In a railway car switching control system, according to claim 21, dummy stopping mechanism adapted responsive to said circuit when open to prevent movement of dummies past it, said circuit being open when said elements are in a predetermined relative position.

26. A railway car switching control system, according to claim 21, in which dummy cars are provided each with means to engage the dummy actuating mechanism and with the number of stop elements corresponding to the number of circuit closing devices on its respective "control" railway car, in combination with dummy stop means operable to disengage the dummy from its actuating mechanism and stop it at each break of said circuit.

27. In a railway car switching control system, a railway track section having at each terminus a wheel actuated trip mechanism, a corresponding dummy track section having a dummy actuating mechanism associated therewith which is responsive to either terminal trip mechanism for moving dummies across a corresponding terminus of the dummy section, said dummy actuating mechanism being selectively responsive to contemporaneous actuations of terminal trip mechanisms which serve to actuate it in different directions.

28. In a railway car switching control system, according to claim 27, means to cause said dummy actuating mechanism when energized by either terminal trip mechanism to continue to operate responsive to said energization until a predetermined relative movement of dummies to cars has been completed.

29. In a railway car switching control system, railway car trip controlled mechanism for actuating dummies, which comprises coil spring driving belts and a drive therefor, and dummies having coupling elements adapted to operatively engage said belts.

30. In a railway car switching control system, railway car trip controlled mechanism for actuating dummies, which comprises coil spring driving belts and a drive therefor, dummies having coupling elements adapted to operatively engage said belts, and stop means adapted in moving to engage a dummy to uncouple it from its driving belt.

31. In a railway car switching control system, railway car trip controlled mechanism for actuating dummies which comprises conveyors and drive means therefor, dummies having stop lugs and coupling elements adapted to engage said conveyors, and stop means also controlled by the railway trip mechanism and comprising a reciprocable stop adapted to co-act with said lugs when

in operative position and carrying a spring-pressed switch arm which in the inoperative position of said stop co-acts with said lugs, means to uncouple the dummy from a conveyor as the stop moves to operative position, and electro-magnetic means controlled by said switch arm to start and stop the drive of the conveyor.

32. In a railway car switching control system, car trip controlled means adapted to move a dummy responsive to its "control" railway car, mechanism controlled by the dummy movement to cause it to advance step by step, and means responsive to the completion of a predetermined controlled dummy movement to lock it in position until a controlling car trip is again actuated.

33. In a railway car switching control system, car trip controlled means adapted to move a dummy responsive to its "control" railway car, mechanism operative responsive to the dummy movement to cause it to advance step by step, and means responsive to the completion of a predetermined controlled dummy movement to lock it in position until a controlling car trip is again actuated.

34. In a railway car switching control system, car trip controlled means adapted to move a dummy responsive to its "control" railway car, mechanism controlled by the dummy movement to cause it to advance step by step, and means responsive to the completion of a predetermined controlled dummy movement to lock it in position until a controlling car trip is again actuated, the mechanism for effecting the step by step dummy movement comprising an escapement feed means co-acting with the dummy.

35. In a railway car switching control system, car trip controlled means adapted to move a dummy responsive to its "control" railway car, mechanism controlled by the dummy movement to cause it to advance step by step, and means responsive to the completion of a predetermined controlled dummy movement to lock it in position until a controlling car trip is again actuated, the mechanism for effecting the step by step dummy movement comprising an escapement feed means co-acting with the dummy, and the lock means comprising mechanism to hold the escapement feed engaged with a dummy.

36. The method for indicating the position and movement of railway cars from track to track in a railway switching yard, which consists in causing the movements of each individual car to present descriptive indicia thereof at a given point in positional relationship to the representation of a trackage system corresponding to that of the railroad switching yard.

37. The method for indicating at a remote point the position and movement of railway cars in a railway switching yard, which consists in providing a representation at such re-

remote point of the tracks of such railway switching yard, causing each individual railroad car to have its identity and position, in respect of said switching yard representation, indicated automatically at such remote point.

38. A mechanism for indicating at a remote point the shifting of railway vehicles in a railway switching yard, which comprises means at such remote point to indicate the several sections of the railway yard tracks, and means controllable by the movement of the railway vehicles in said railway switching yard for indicating, by reference to said first mentioned means, the identity and the changing position of individual vehicles as they are shifted about the railway yard tracks.

39. In apparatus for indicating position and movements of a plurality of railway vehicles in a multiple track railway yard, means indicating the separate tracks in said yard, means indicating and identifying the separate railway vehicles in said yard in association with the respective tracks they occupy, and means responsive to shifting of a vehicle on the tracks on the yard for altering its respective indicating means to correspond to its new position.

40. The method for indicating the position and movement of railway vehicles in a multiple track railway yard, which consists in providing separate indicia for the separate tracks in said yard, and causing the separate vehicles to present identifying indicia in association with the indicia for the tracks they occupy.

41. Process of governing the movements of cars in a railroad switchyard, characterized by the provision, in a model dummy switchyard, corresponding to the railroad switchyard, of dummies, indicated to correspond with their respective cars in the railroad switchyard, which dummies are moved automatically backwards and forwards, and from track to track, in correspondence with the movements of their respective corresponding railroad cars, and in which the movement of car wheels into and out of a given railroad track section will cause a corresponding movement of wheel indicators into and out of a corresponding track section of the dummy yard, which is characterized by the fact that, in the event of wheel movements which normally effect dummy actuating mechanism for a given track section occurring while said actuating mechanism is actively responding to a preceding actuation effected by wheel movements in an opposite direction to the first mentioned wheel movements, the first mentioned wheel movements will be recorded and held unsatisfied until the other of said wheel movements has been satisfied, at which time said unsatisfied wheel movement will become effective in actuating

the said dummy actuating means in a corresponding direction.

42. A process according to claim 41, in which a common reversible actuating means for the dummies in a given dummy yard track section will respond successively to concurrent opposed car movements in a corresponding section of the railroad switchyard, the last car movement to commence having its control of a corresponding dummy movement held in suspense while the movement first to commence is controlling the dummy movement.

43. In an apparatus of the character described, a dummy switchyard having track section and switches corresponding to the track sections and switches of a railroad switchyard, dummies movable over said dummy switchyard and having wheel indicators, actuating means for moving dummies by their wheel indicators into and out of a given dummy track section, agencies responsive to the movement of car wheels at the ends of the corresponding railroad yard track section for controlling said actuating means and effecting a movement corresponding in number and direction of dummy wheel indicators, in combination of means which will record and hold in suspense movements to be imparted in one direction to dummy wheel indicators until completion of movements being imparted in the opposite direction to dummy wheel indicators in the same dummy track section.

In testimony whereof I affix my signature. 100
LEON M. GIBBS.
